US0D1015694S

(12) United States Design Patent (10) Patent No.: US D1,015,694 S
(45) Date of Patent: * Feb. 27, 2024

(54) FOOTWEAR

(71) Applicant: Target Brands, Inc., Minneapolis, MN (US)

(72) Inventors: Ashley Damian, Minneapolis, MN (US); Megan Ganley, Boston, MA (US); Sara Swenson, Minneapolis, MN (US)

(73) Assignee: Target Brands, Inc., Minneapolis, MN (US)

() Term: 15 Years

(21) Appl. No.: 29/890,686

(22) Filed: Apr. 26, 2023

Related U.S. Application Data

(62) Division of application No. 29/803,433, filed on Aug. 12, 2021, now Pat. No. Des. 987,950.

(51) LOC (14) Cl. 02-04

(52) U.S. Cl.

USPC D2/923

(58) Field of Classification Search

USPC D2/896, 898, 899, 900, 916, 917, 919, D2/923–926, 943, 946, 969, 972

CPC A43B 1/0081; A43B 3/12; A43B 3/10; A43B 3/102; A43B 13/00

(57) CLAIM

The ornamental design for a footwear, as shown and described.

DESCRIPTION

FIG. 1 is a front, top and left side perspective view of an embodiment of a footwear according to the new design;

FIG. 2 is a front side elevation view thereof;

FIG. 3 is a back side elevation view thereof;

FIG. 4 is a left side view thereof;

FIG. 5 is a right side view thereof;

FIG. 6 is a top plan view thereof;

FIG. 7 is a bottom plan view thereof; and,

FIG. 8 is a back, bottom and right side perspective view thereof.

The broken lines in the drawings show portions that form no part of the claimed design.

1 Claim, 7 Drawing Sheets
